DELINEATING MULTICOLORED DESIGNS
ON FABRIC

William M. Trainor, New York, N. Y.

Application June 16, 1937, Serial No. 148,443

6 Claims. (Cl. 101—115)

This invention relates to the art of delineating multi-colored designs on fabric by means of stencils.

More especially the invention relates to the application of such multi-color designs to cut pieces of fabric such as blanks to be made into articles such as aprons, laundry bags, pillow cases, guest towels and the like articles.

Such articles are intended primarily to be embroidered by the retail purchaser with threads corresponding in color to the respectively different color components of the multi-color design delineated thereon and which design is to be outlined by such embroidery.

Heretofore, such designs were outlined on the fabric pieces, as by means of a stencil, in a single color, such as black or blue, and a chart was furnished with each piece as a guide to indicate the preferred or intended color scheme. Later, multiple color outlines were employed, but prior to the present invention the number of colors has been limited and the work has been slow and expensive on account of the methods and apparatus heretofore employed.

For instance, on articles such as aprons, laundry bags and the like, where the sizes are relatively large, difficulty has been experienced in applying the colors and the speed of production has been very limited with attendant relatively high cost. Furthermore, it has only been found practical heretofore to utilize a maximum of three colors. In such articles the retail sales price is low and since the designs are applied to the blanks individually by repeated operations, rapidity of production is an important item.

An object of the invention is to provide a method of and apparatus for applying to pieces of fabric multi-colored designs comprising as many component colors as desired.

A further object is to provide a method of and apparatus for applying such designs to large pieces of fabric in an improved and efficient manner and at an increased speed, with equal or better registration of the individual colors.

Further and more specific objects, features and advantages will more clearly appear from the detailed description given below taken in connection with the accompanying drawing which forms a part of the specification.

The invention consists in the method herein described and in the novel features, arrangement, construction and combination of parts of the apparatus and means hereinafter described in accordance with certain preferred embodiments

thereof, and the invention will be more particularly pointed out in the appended claims.

Further objects of the invention will more fully appear from the following description taken in connection with the accompanying drawing illustrating by way of example the preferred embodiment of the apparatus used in carrying out the method.

In the accompanying drawing, showing by way of example a present preferred embodiment of the invention:

Fig. 1 is a plan view of the apparatus,

Fig. 2 is a side view, in elevation, of the apparatus of Fig. 1, and

Fig. 3 is a cross-sectional view, in elevation, taken at 3—3 of Fig. 1.

Referring to the drawing: 1 is a table comprising a top 2 and suitable legs such as 3. The table top is preferably provided with an upper surface such as a rubber composition, felt or cloth pad or the like to prevent pieces of cut fabric or blanks placed thereon from readily slipping or becoming displaced during operation and further to provide a slight resiliency. In the present embodiment, a table top of the order of 8½ feet square has been found satisfactory in the production of articles of the size of women's aprons, laundry bags, pillow covers and the like.

Positioned above the table 1 is a stencil carrier or frame 4, which in the present embodiment is square in form and comprises four panels for the accommodation of a like number of stencils; permitting, in this instance, the utilization of four colors in the design. This frame is carried on the upper end of a shaft or axle 5 to which it is rigidly attached at its central point. The shaft passes through a bearing 6 positioned at the center of the table and extends downwardly, passing through a bore in a suitable pedestal 7, and terminating in a rounded end 8 which rests on the inner end of a lever 9. The lever 9 is supported on a fulcrum base 10 as by means of a pin 11 and is provided with an outer end 12 in the form of a treadle for engagement by the operator's foot. An adjustable weight 13 is positioned so as to substantially balance the frame 4 and parts carried thereby but permits the frame and attached parts to move downwardly by gravity when the treadle is released.

The pedestal 7 is provided at its upper end with four equidistantly circumferentially spaced vertical slots, such as 14. These slots are arranged in pairs, each pair being diametrically positioned relative to the shaft 5, and the slots are each provided with a gradually widened flar-

ing upper portion. A pin 15 extends transversely through the axis of the shaft 5 and is of a size to snugly engage the vertical side walls of the slots 14; the flaring or round upper ends of the slots serving to center or guide the pin into the slots when the shaft 5 is lowered, so that the respectively opposite ends of the pin 15 will engage the corresponding diametrically opposite slots 14. The relative position and arrangement 10 of the parts is such that when the shaft is in its lowermost position the pin serves to hold the shaft in a definite fixed angular relation, and when the shaft 5 is raised to the dotted position indicated the pin is positioned above the upper 15 extremities of the pedestal portions intermediate the slots 14 to thereby permit angular movement of the shaft 5 about its axis.

In the present design illustrated, four colors are employed and the design is therefore to be applied by means of four stencil sheets each bearing a complementary increment of the design through which the respectively corresponding color of that increment of the design is to be applied to the fabric positioned on the upper surface of 20 the table 1. These stencils are made in a manner well known to those skilled in the art and usually are formed of a relatively thin parchment or stencil paper, which is perforated in outline 25 corresponding to the desired configuration of the design. These four stencil sheets are respectively designated in Fig. 1 as 16, 17, 18 and 19; the stencil sheet 16 bearing the complementary design increment or stem 20 which is to be outlined in brown on the fabric, the stencil sheet 17 bearing 30 the complementary design increment or petal unit 21 which is to be outlined in blue on the fabric, the stencil sheet 18 bearing the complementary design increment or leaves such as 22 which are to be outlined in green on the fabric, and the 35 stencil sheet 19 bearing the complementary design increment or pistils 23 which are to be outlined in red on the fabric. The four stencil sheets are supported and positioned in proper 40 register on the frame 4; in the present illustrated apparatus this registration has been satisfactorily 45 effected and the stencils attached in the following manner.

Starting with the stencil 16, which position in the drawing will be designated as station A, the 50 complete design of the flower comprising the increments 20, 21, 22 and 23 is secured to the table 1 and properly centered within the panel of the frame at that station. The stencil sheet 16 is then placed over the complete design so as to be 55 in accurate register with the corresponding increment thereof and the sheet is secured to the frame in the manner illustrated in Fig. 3, i. e. one edge of the sheet is passed underneath the radially extending rib of the frame 4 at the left 60 hand of this position and is secured to the frame 4 by suitable means such as thumb tacks 24, which permit an easy means of adjusting the registration of the increment 20 with the master design; while the opposite or outer edge of the 65 stencil sheet is passed around the marginal side of frame 4 and suitably secured thereto, as by means of spring clamps such as 25. After the stencil is thus secured in registered position, the inner edge is preferably clamped tightly in position as by means of clamping strips 26-27 and 70 cooperating C clamps 28-29.

It is particularly noted that the stencil sheet is secured to the frame at two opposite edges only, since I have found that in the apparatus illustrated, and especially in utilizing stencils of large 75

area made of relatively thin material such as paper or the like, the stencil tends to wrinkle, when used, if attached to the frame at each of its edges; and I have found that when secured in register by being held along two respectively 5 opposite edges and by applying the color medium in a direction from one to the other of said attached edges, excellent results are obtained.

When the stencil 16 has been secured in registered position, the treadle 12 is depressed to raise 10 the frame 4 to the upper position indicated by dot and dash lines (Fig. 2) and the frame rotated in a clockwise direction approximately 90°, then the treadle pressure is released to lower the frame so that the second panel is placed in fixed position at station A and over the master design; the slots 14 and pin 15 serving to accurately center the frame. In order to avoid any possible displacement of the outer portions of the frame, due to its large size, I have also provided means 20 for accurately and rigidly locking the frame adjacent its outer margin, such as by means of L brackets 30, one of which is attached to the frame 4 at each corner, and a pin 31 which is inserted through a hole in said bracket and into a cooperating hole in the table top 2 in accurate registration therewith when said frame is in proper position.

With the frame thus fixed in position, the stencil 17 is secured to the frame in the manner previously described relative to stencil 16, so that the design increment 21 is properly registered with the corresponding portion of the master design. The pin 31 is then removed and the stencils 18 and 23 are similarly secured to the frame in proper register with the master design 35 carried on the table 1.

It will thus be seen that the four stencils 16, 17, 18 and 19 are secured to the frame 4 in predetermined register about the axis of the shaft 40 5 as a focal center and in spaced relation to each other around said focal center. The increment 20 corresponds to that portion of the complete design to be colored in one color, say brown, and similarly the other increments 21, 22 and 23 to the 45 respective portions of the complete design to be colored, say, blue, green and red.

Method

While the method may be carried out by applying or delineating the multi-colored design on a single piece of fabric at a time by applying the respective individual increments successively to a single piece of fabric until the design is completed, one of the advantages of the present invention resides in the ability to operate upon a plurality of pieces of fabric simultaneously in a number equal to the number of colors utilized, in the present embodiment four; and accordingly, this more rapid production will be described.

In operating upon only one piece of fabric at a time, one person only is needed to carry out the process, while in operating upon a plurality of pieces of fabric at a time it has been found advantageous to have a plurality of persons each handling one of the individual colors, and this is particularly true in handling relatively large sized fabric pieces as previously referred to.

With the stencils arranged in registration series as previously described, and with the stencils held above the supporting means such as table 1 for the fabric, the pieces of fabric are spread out on the table in a group around the focal axis of registration of the stencils and spaced thereabout corresponding in general to 70 75

the spacing of the stencils, i. e., in the position shown in Fig. 1 there will be one piece of fabric at station A, one at station B, one at station C, and one at station D. The four stencils are then simultaneously lowered and each of the stencils brought into respective registration with its corresponding piece of fabric and the stencils held in this position as by means of the slots 14 and pin 15 and the brackets 30 and pins 31, previously described. The pieces of fabric at stations A and D are designated in Fig. 2 as *f*. An operator at station A wipes a suitable color medium, such as a brown pigmented fluid of a suitable thickness, across the stencil increment 20 in a direction from the left to the right or right to left so as to cause the brown fluid to pass through the perforations of the stencil onto the piece of fabric against which the lower face of the stencil rests. A simple rubber strip held in a wooden handle has been found satisfactory for wiping colors on the stencils so as to print the design on the fabric. Simultaneously, a second operator at station B forces a blue fluid through the stencil 17 by wiping in a direction from the bottom toward the top or from the top toward the bottom to thereby print the increment on the fabric at that station, and at the same time operators at stations C and D similarly apply the respective colors green and red so as to print the stencil increments 22 and 23 upon the fabric pieces at those respective stations; the colors always being applied in a direction between the attached ends of the stencils. We have now one increment of color applied to each of the four pieces of fabric. The four stencils are now simultaneously raised from contact with the fabric pieces, in a vertical direction to prevent smearing (and the stencils are simultaneously rotated about the axis of shaft 5 for approximately 90°) and are simultaneously lowered into exact registration respectively with the pieces of fabric, each stencil now being in register with the immediately succeeding piece of fabric of the spaced-apart series. For example, the operator at station A now applies the increment design 21 to his piece of fabric, the operator at station B applies the increment 22 to his piece of fabric, the operator at station C applies the increment 23 to his piece of fabric, and the operator at station D applies the increment 20 to his piece of fabric—each operator utilizing the color fluid corresponding to the increment which he applies at a given time. The process is repeated until the four colors have been applied to each of the four pieces of fabric, whereupon the stencils are lifted and the four completed fabric pieces removed and the process repeated. After repeated use of the stencils, there is a tendency for the fluid colors to gradually build up and become hardened, but as is well understood by those skilled in the art this may be remedied by suitable cleansing of the stencils with a solvent. As an example of a fluid color medium I might mention the use of pigment ground in oil and mixed with lard or the like to the desired consistency for the particular type of work in hand; and with this type of color medium I have found kerosene a suitable solvent to clean the stencils if necessary.

The invention contemplates a plurality of colors in excess of or less than the number of four hereinabove referred to. In using colors in excess of four, the supporting means for the stencils is correspondingly adapted to carry the num-

ber of stencils desired in a series about a common axis in the manner heretofore described. For example, instead of a square frame a circular frame having the general form of a cart-wheel could be utilized, wherein the circle would be divided into a number of equal segments corresponding to the number of colors desired to be utilized. 5

Having thus described my invention with particularity with reference to the preferred method of carrying out the same and in connection with the preferred apparatus for carrying out the same, and having referred to some of the possible modifications thereof, it will be obvious to those skilled in the art, after understanding my invention, that other changes and modifications may be made therein without departing from the spirit and scope of my invention, and I aim in the appended claims to cover such changes and modifications as are within the scope of the invention. 10 15 20

What I claim is:

1. In a device for delineating a multi-colored design on fabric, the combination of a substantially horizontal table for supporting a fabric to which said multi-colored design is to be applied, a substantially horizontal frame for carrying in substantial parallelism therewith a plurality of stencils bearing respective individual complementary increments of said design, said table and frame being relatively movable one with respect to the other in an angular direction about a substantially vertical axis coincident with a focal registration point for said increments of design and said frame being movable toward and away from said table in a direction substantially parallel to said axis, said frame having a plurality of substantially radially extending arms between respective of which and relatively opposite frame portions said stencils are held, said frame being so constructed and arranged that one corresponding side of each stencil is attached to its respective arm and an adjoining side of each stencil throughout a major portion of its length lies contiguous to an adjacent arm to which another of said stencils is attached and means for guiding said frame in its angular and reciprocal movements respectively about and along said axis. 30 35 40 45

2. In a device for delineating a multi-colored design on fabric, the combination of a substantially horizontal table for supporting a fabric to which said multi-colored design is to be applied, a substantially horizontal frame positioned above and in substantial parallel relationship to said table and pivotally supported for movement about a substantially vertical axis, said frame providing means for carrying on the lower side thereof a plurality of stencils bearing respectively complementary increments of design equidistant in a radial direction from said axis as a common focal point of registration and spaced circumferentially relative to each other about said pivot point, said frame having a plurality of substantially radially extending arms between respective of which and relatively opposite frame portions said stencils are held, said frame being so constructed and arranged that one corresponding side of each stencil is attached to its respective arm and an adjoining side of each stencil throughout a major portion of its length lies contiguous to an adjacent arm to which another of said stencils is attached means operable to substantially vertically raise said frame away from and lower said frame adjacent to said table, 50 55 60 65 70 75

and means for holding said frame against rotation while in its lowered position.

3. The method of delineating a multi-colored design on pieces of fabric or the like which comprises supporting a plurality of pieces of said fabric in a substantially circular series in spaced-apart relation and substantially concentric to a focal axis, supporting a like plurality of stencils each bearing a complementary increment of the desired design above said surface and in spaced relation to said fabric with the respective stencils each held in fixed register with respect to each other and about said focal axis and all lying in a substantially horizontal plane, said stencils being grouped with two adjoining sides of each throughout the major length of said sides lying contiguous respectively to one side each of two respectively adjacent stencils simultaneously angularly moving said stencils about said axis while holding said stencils in spaced parallel relation to said fabric, successively bringing said individual stencils simultaneously into registered engagement with respective of said fabric pieces while said angular movement is suspended and simultaneously applying colored fluid media through said respective stencils onto said fabric pieces while said individual increments of design are respectively held in fixed register with said fabric pieces.
- 30 4. In a device for delineating a multi-colored design on fabric, the combination of means for supporting said fabric in substantially flat condition, means for supporting a plurality of stencils each being a complementary increment of the desired design in substantial parallelism with said surface with the respective stencils each held along two opposite edges only and in fixed register with respect to each other about a common axis extending substantially normal to said fabric-supporting means, said stencil supporting means having a plurality of substantially radially extending arms between respective of which and relatively opposite frame portions said stencils are held, said supporting means being so constructed and arranged that one corresponding side of each stencil is attached to its respective arm and an adjoining side of each stencil throughout a major portion of its length lies contiguous to an adjacent arm to which another stencil is attached, means for holding said stencil support in raised position above said fabric support and guiding said support in angular movement about said axis and for moving said stencil support along said axis toward and away from said fabric support, whereby said stencils may be supported free from engagement with said fabric while simultaneously moved in an angular direction to bring respective stencils into registered position and may be simultaneously moved in a direction parallel to said axis to bring respective stencils into registered engagement with said fabric after said angular movement has been completed.

5. In a device for delineating a multi-colored design on fabric, the combination of substantially horizontal means for supporting the fabric onto which said multi-colored design is to be applied, a substantially horizontal stencil supporting frame positioned over said fabric-supporting means and movable angularly relative to and in a direction normal to said fabric-supporting means, said frame having a plurality of substantially radially extending arms and relatively oppositely disposed corresponding frame portions spaced therefrom, a plurality of stencils carried by said frame and respectively bearing individual complementary increments of said design, said stencils being arranged in a series substantially parallel to said frame and secured to respective arms and said relatively opposite frame portions, said frame being so constructed and arranged that one corresponding side of each stencil carried thereby is attached to its respective arm and an adjoining free side of each stencil throughout a major portion of its length lies contiguous to an adjacent arm to which another stencil is attached, and means for guiding said stencil frame in angular movement about said axis and in reciprocal substantially vertical movement along said axis toward and away from said fabric-supporting means.

6. In a device for delineating a multi-colored design on fabric, the combination of means for supporting a plurality of pieces of fabric onto each of which said multi-colored design is to be applied, stencil supporting means positioned over and substantially parallel to said fabric-supporting means and movable angularly relative to and in a direction normal to said fabric-supporting means, a plurality of stencils equal in number to said pieces of fabric and carried by said last means in substantial parallelism therewith and respectively bearing individual complementary increments of said design, said stencils being secured in predetermined register about an axis common to said design and which extends substantially normal to said stencil supporting means, said stencil carrying means having a plurality of substantially radially extending arms between respective of which and relatively opposite frame portions said stencils are held, said stencil carrying means being so constructed and arranged that one corresponding side of each stencil is attached to its respective arm and an adjoining side of each stencil throughout a major portion of its length lies contiguous to an adjacent arm to which another of said stencils is attached, said stencil carrying means serving to simultaneously move said stencil about its axis and to individually bring respective increments of said design simultaneously into successive predetermined register with said pieces of fabric, and means for guiding said stencil supporting means in angular movement about said axis and in reciprocal movement along said axis.

WILLIAM M. TRAINOR.
